DECANTER

Ernest L. Du Pree, New York, N.Y., assignor to Schenley Industries, Inc., New York, N.Y., a corporation of Delaware

Filed Sept. 25, 1962, Ser. No. 71,837

Term of patent 14 years

(Cl. D58—6)

The side not shown is substantially the same as the side illustrated and the rear face of the decanter is substantially plain.

I claim:

The ornamental design for a decanter, as shown and described.
